US00D851508S

(12) **United States Design Patent** (10) **Patent No.:** **US D851,508 S**
D'Eramo (45) **Date of Patent:** **** Jun. 18, 2019**

(54) **EXTERNAL SENSOR ASSEMBLY FOR A VEHICLE**

(71) Applicant: **Uber Technologies, Inc.**, San Francisco, CA (US)

(72) Inventor: **Christopher D'Eramo**, Pittsburgh, PA (US)

(73) Assignee: **Uber Technologies, Inc.**, San Francisco, CA (US)

(**) Term: **15 Years**

(21) Appl. No.: **29/563,210**

(22) Filed: **May 3, 2016**

(51) LOC (11) Cl. **10-04**

(52) U.S. Cl. **D10/70**
USPC ....

(57) **CLAIM**

The ornamental design for an external sensor assembly for a vehicle, as shown and described by the figures.

DESCRIPTION

FIG. 1 is a front isometric view of an external sensor assembly for a vehicle;

FIG. 2 is a rear isometric view of the external sensor assembly for the vehicle;

FIG. 3 is a front view of the external sensor assembly for a vehicle;

FIG. 4 is a rear view of the external sensor assembly for a vehicle;

FIG. 5 is a first side view of the external sensor assembly for a vehicle;

FIG. 6 is a second side view of the external sensor assembly for a vehicle;

FIG. 7 is a top view of the external sensor assembly for a vehicle; and,

FIG. 8 is a bottom view of the external sensor assembly for a vehicle.

The broken lines shown in the drawings are for the purpose of illustrating the environment of the external sensor assembly, and form no part of the claimed design. The broken lines depicting a vehicle in FIGS. 1 and 2, are for environmental purposes only, and form no part of the claimed design.

1 Claim, 6 Drawing Sheets
